GILL-DRAWING FRAME

Filed Oct. 15, 1940

UNITED STATES PATENT OFFICE

2,289,870

GILL-DRAWING FRAME

Ralph C. Berker, Hoxie, R. I.

Application October 15, 1940, Serial No. 361,298

1 Claim. (Cl. 19—129)

This invention relates to gill-drawing frames or like machines, and consists in improvements in the arrangement of supporting the top half of the hinge-opening intersecting head carrying the upper pairs of screws in an open position with respect to the lower half of the head housing the lower set of screws.

Another object of the invention is to provide in a gill drawing frame means for holding the gill screws in the top half of the intersecting head in an open position away from the lower set of screws for ready access to the mechanism without requiring the use of the well known abutment ears on the hinge members and the chain supported weight as commonly used at the present time for counterweighting the movable top half.

Another object of the invention is to provide a prop device which may be constructed in the form of an attachment adapted to be applied to gill drawing frames of usual design and construction without material alteration or reconstruction thereof.

With these and other objects in view, the invention consists of certain novel features of construction, as will be more fully described, and particularly pointed out in the appended claim.

In the accompanying drawing:

Fig. 1 is a side elevational view of the hinge-opening head member housing the upper and lower sets of gill screws and faller bars of the gill drawing frame construction shown in Patent No. 1,876,936 to which is applied my invention;

Fig. 2 is a similar view illustrating the upper half section of the head member swung open with the upper and lower pairs of gill screws in a separated relationship;

Fig. 3 is a fragmentary front elevational view, partly in section showing the gill screws and the faller bars mechanism at one side of the machine with the faller bars of one set in operative relation to those of the other set;

Fig. 4 is a fragmentary front elevational view of the gill head member showing applied thereto a modified form of bracket mounting carrying the swingable prop member; and

Fig. 5 is a fragmentary front elevational view of the gill head member showing applied thereto another modified mounting support member carrying the swingable prop element.

One prior construction of gill drawing frame in common use at the present time is that shown and described in Patent No. 1,876,936 to Holdsworth, dated September 13, 1932, having a hinge-opening head housing the upper and lower sets

of gill screws and faller bars. In this prior form of construction, the cooperating hinge parts have been provided with upper and lower laterally projecting flanges or lugs which are disposed with their end faces in position to strike each other to form a stop for limiting the maximum extent of opening movement of the upper half of the hinged head when it is swung open. It has been found, however, that in the use of this prior structure the hinge itself sometimes snaps off, while in many instances the laterally projecting flanges or lugs often break off if they are subjected to a sudden and violent impact against each other as would occur when the top half of the head is lifted too quickly and allowed to drop back by the pulling action of a heavy weight which is usually suspended from one end of a chain such as a bicycle chain, which passes over a pulley and carries a washer on its other end by which the chain is detachably secured to some projecting part on the movable upper half of the hinged head member, such as the head of a bolt; and in order to stop breakage of the hinge parts and to avoid the aforementioned difficulties, and also to eliminate the use of the prior weighted chain and the potential hazard created thereby of the chain becoming accidentally dislodged from its anchorage and the weight dropping on the foot of the operator, I have provided in accordance with the present invention a device which may be attached to a stationary part of the frame and so constructed and arranged as to have interlocking relation with a part on the movable upper half of the hinged head member of the gill box whenever the same is swung open to afford ready access to the interior thereof, and this device comprises a swingable prop having a slot which is so shaped as to enable sliding movement of the cooperating element on the upper half of the hinged head as the same is swung open and with the upper portion of the slot so shaped as to be self-locking under the weight of the wide-opened gill head to sustain it in its opened position; and the following is a more detailed description of the present embodiment of this invention, illustrating the preferred means by which these advantageous results may be accomplished:

With reference to the drawings, 10 generally designates one of a pair of hinged journal blocks or bearing head members of similar construction and arrangement located at opposite sides of the gill drawing frame and housing the usual gill screw mechanism, the construction being substantially the same as described in Patent No.

1,876,936 to Holdsworth, dated September 13, 1932, and comprising the upper and lower halves or sections 12 and 13 respectively of the block 10. The upper pair of gill screws 15 and 16 which traverse the set of faller bars 17 are journaled in the upper hinged section 12 while the lower pair of gill screws 18 and 19 for traversing the set of faller bars 20 are journaled in the lower hinged section 13, all of which construction is usual in the art. Suitable lugs or ears 21 and 22 are provided having slots 24 and 25 for receiving the bolts which attach the usual faller guides (not shown) in proper relation to the gill screws. Bolts 26 passing through suitable holes in the frame and screwed into the side of the bottom section 13 of the block 10 serve to rigidly attach the same to the side of the machine.

The upper half section 12 of the journal block normally rests against the flat top face 20 of the lower half section 13, the joint being broken with a vertical shoulder as at 31 to form a ledge or offset portion which holds the two sections 12 and 13 in alignment when they are closed, as illustrated in Fig. 1. The upper section may be arranged to move away from the lower section in any suitable manner and, preferably, a hinged joint 33 is provided with its axis substantially coincident with the parting line between the two half members 12 and 13. The hinge 33 between the two sections 12 and 13 may be constituted by the ears 35 and 36 projecting from the rearward side of each section and formed with the hubs 37 respectively, through which extends a pivot pin or stud 39 suitably held in place by a washer and nut (not shown).

The upper ear 35 has a laterally projecting flange or lip 40 disposed with its end in position to strike against the projecting flange or lip 41 on the lower ear 36, see Figs. 1 and 2, whereby to form a stop for limiting the opening movement of the upper half section 13 when it is swung open as illustrated in Fig. 2.

A square-headed bolt 43 passes down through a hole 44 in the upper half section 12 of the journal block 10 and has its lower threaded end screwed into a tapped hole 44' in the lower half section of the block 10 to hold the two halves of the block 10 in connected relationship.

In order to support the upper half section 12 of the gill head member 10 when it is swung wide open for ready accessibility to the gill screw mechanism and the faller bars, I have provided in accordance with this invention a device comprising a bracket member 45 which is suitably fastened, as by studs 46, to the lower half section 13 of the head 10, and pivotally mounted at the upper end portion of the bracket member 45 is a swingable arm 48 provided therein with a slot 49 extending longitudinally and substantially diagonally thereof. A pin 50 carried by and projecting from a side of the top half section 12 of the head is slidably received in the slot 49. Formed at the free end of the arm member 48 and communicating with the slot 49 is a lateral recess or crook 51 which is so shaped as to accommodate and receive the pin 50 when the same is slid the entire length of the slot 49 to the free end thereof and thence laterally into the recess

51 when the top half section 12 of the head is swung into an open position, the weight of the top half section 12 acting to hold the pin 50 in engagement with the bottom of the recess 51 and the arm member 48 serving as a prop to support the upper section 12 at an oblique angle and in a separated relation with respect to the lower section 12. When in this separated position the arrangement of the arm 48 will be such that the flanges 40 and 41 will not be in abutting relation but instead will be held slightly separated, as shown in Fig. 2, whereby there will be no impingement of the flanges during opening of the upper half section 12.

15 In Fig. 4 there is shown a modified arrangement in which the arm member 60 is of similar slotted construction to the swingable arm 48 but instead is suitably pivoted as by a bolt 61 to the top portion of a bracket 62 which is undercut 20 as at 63 for mounting on the top edge 64 of the side plate member 65 of the frame of the machine where it may be held in place by bolts 66.

Another modified arrangement is shown in Fig. 5, in which the pivoted slotted arm member 70 25 is suitably pivoted to the side face of a block 71 as by means of a bolt 72, and the block bolted by studs 73 directly to the top face of the side plate member 74 of the machine.

The foregoing description is directed solely towards the construction illustrated, but I desire it to be understood that I reserve the privilege of resorting to all the mechanical changes to which the device is susceptible.

I claim:

35 In a gill drawing frame or like machine having upper and lower hinged sections providing a separable head housing the gill screw mechanism including the intersecting comb members, of a device for holding up the upper section of said head in a separated relation from said lower section when said upper section is lifted and swung upwardly from said lower section, said device comprising an arm member of equal width throughout its length and pivoted at one end portion thereof to one of said hinged sections and having a slot extending generally diagonally of the arm terminating in proximity to the upper free end of said arm, and a pin on the other hinged section of said head accommodated within 50 and in engagement with said slot, the free end of said arm being provided with a recess extending laterally of said arm and in communication with the upper end of said slot to provide a crook extension therein for receiving said pin at the completion of its sliding movement in the longitudinal direction of said slot to the upper end thereof to support said arm when acting as a prop to hold the upper hinged section of said head in a raised position from said lower hinged section, the arrangement being such that the pin will initially occupy a position at one side of the pivot axis of said arm when the sections are closed, and will be moved from this position and be located at a position at the other side of the pivot axis of said arm when the upper hinged section is held in a raised position by said arm.

RALPH C. BERKER.
